UNITED STATES PATENT OFFICE.

EDWARD A. ROBB, OF ST. LOUIS, MISSOURI.

THROTTLE-CONTROLLING MEANS FOR INTERNAL-COMBUSTION ENGINES.

Application filed April 6, 1926. Serial No. 100,134.

This invention relates to means for regulating the feed of fuel to the motor of a motor driven vehicle and particularly to devices of this general character in which 5 a governor is used which maintains or tends to maintain a certain uniform speed.

One of the objects of this invention is to provide a device of this character which will automatically regulate the feed of fuel 10 to the engine and cause the motor to maintain or tend to maintain a uniform speed over differences in the grade of the roadway without necessitating any adjustment of the hand operated throttle controlling means or 15 of the accelerator, the rate of speed, of course, being governed by the position of the throttle and varied by each movement thereof.

A further object is to provide a mechanism 20 of this character particularly applicable to passenger cars but adapted to be used with other types of motor driven vehicles and to some motor driven vehicles without changes in their general construction, which 25 is so formed that the flow of fuel at all speeds of the engine will be subject to a dual control, that is, to the control operated by the driver and to a control operated by the speed of the motor, and in this connection 30 to provide a mechanism of this character which will operate without interfering with the direct connection between the driver's control and the carburetor and which will not reduce the promptness with which the 35 motor operates in response to that control.

Another object is to provide a mechanism 40 of this character which will cause the power of the motor driven vehicle to increase automatically, regardless of the speed of the 45 motor when a hill is approached, when the vehicle is going up a hill, and to cause the power of the motor to decrease when the vehicle reaches the top of the hill.

A further object is to provide a controlling mechanism which will eliminate 50 much of the manipulation of the hand throttle or of the accelerator by the driver and thus make the driving of the vehicle much simpler.

A still further object of the invention is 55 to provide throttle valve controlling means which will permit the throttle valve to be set by the driver by the usual operating lever on the wheel to thus determine the speed and which will then operate to maintain or tend to maintain this speed on dif-

ferent grades, permitting, however, the instant operation of the operating lever or the instant opening of the throttle under the action of the accelerator pedal. 60

Other objects will appear in the course of the following description.

My invention is illustrated in the accompanying drawings wherein:

Figure 1 is a top plan view of my invention showing the same connected with a throttle and also illustrating the fan of an internal combustion engine;

Fig. 2 is a rear elevation of the cylinder 65 and the supporting frame;

Fig. 3 is a sectional view on the line 3—3 of Figure 1;

Fig. 4 is a side elevation of the structure shown in Figure 5;

Fig. 5 is a horizontal sectional view 75 through the cylinder and allied parts;

Fig. 6 is an enlarged top plan view of the throttle controlling levers.

Referring to these drawings it will be seen that my device comprises a supporting 80 frame having a base designated 10 and having upwardly extending portions 11 and 12. This base, as illustrated in Figure 2, is transversely concave whereby the frame may be disposed on top of the generator 85 G, as for instance the generator of a Ford automobile.

Mounted in suitable bearings in the forward upwardly extending portion 11 is a shaft 13 carrying upon its forward end a 90 pulley 14 which is connected by a belt to the usual fan shaft of an automobile and which is disposed just behind the fan bracket. The upright portion 12 of the frame is formed to provide a collar 15 and sliding 95 within this collar is a hollow cylinder 16. This cylinder at one end is formed with a head 17 having a central aperture and operating through this aperture of the cylinder is a shaft 18 and disposed on the inner 100 end of this shaft and bearing against the head 17 is a disk 19 which is rotatable with the shaft 18. This constitutes a swivel connection between the shaft 18 and the cylinder 16 which permits the shaft 18 to rotate relative to the cylinder but which causes the cylinder 16 to move longitudinally with the shaft 18. 105

Pivots connected to the shaft 18 are the links or arms 20 of the governor and pivots connected to these links or arms 20 are the links or arms 21 of the governor 110

which in turn are pivotally connected to the inner end of the shaft 13. Thus, it will be seen that as the shaft 13 rotates, the governor will be rotated and the shaft 18 and 5 the disk 19 will be rotated, and that as the speed of rotation increases, the governor arms will be forced outward by centrifugal force and this will act to pull upon the shaft 18 and draw the cylinder 16 inward 10 or toward the governor.

Mounted upon the cylinder 16 is a member 22 providing two diametrically disposed arms and from these arms extend rearward the members 23 which at their inner ends 15 are bent at right angles as at 24. The collar 15 is provided with lugs 25, these lugs being perforated for the passage of headed bolts or screw-threaded rods 26 having thereon the nuts 27. Disposed between the angular ends 20 24 of the arms 23 and these nuts 27 are the coil compression springs 28. Thus when the cylinder 16 is pulled toward the forward end of the machine by the expansion of the governor arms 20, the arms 23 will move with 25 the cylinder against the action of the springs 28, and as the speed is reduced and the centrifugal force is correspondingly reduced, the springs 28 act to push against the arms 23 and force the cylinder 16 rearward or 30 away from the front of the machine.

In Figure 4 I have shown and illustrated a conventional carburetor designated generally C. This carburetor has a stem c and a throttle valve D mounted upon the stem and rotating therewith from a fully closed to a 35 fully opened position. Rigidly mounted upon this stem c is a lever 29 and one portion of this lever is reduced in thickness as at 30, and mounted upon this reduced portion is a slide 31. This slide has an angularly and laterally projecting arm 32 provided at its extremity with the pin 33 and this arm operates within a slot 34 formed in one arm of the lever 35, this lever being loosely 40 mounted for oscillation upon the stem c. The opposite end of this lever is adapted to be connected to a rod 36 which is operatively connected to the throttle controlling lever on the steering wheel of the automobile and operatively connected to the accelerator pedal 45 in an obvious manner, such, for instance, as shown in Figure 1.

Pivotally connected to the slide 31 is a link or rod 37 which extends forward and is 50 pivotally connected to the stem 38 extending outward from the cylinder and more specifically from the member 22. Under these circumstances it will be seen that, assuming that the lever 35 has been set in a predetermined position by the rod 36 leading from the hand throttle controlling means, when the governor is expanded under an increase 55 in speed the cylinder 16 will be pulled forward and this will pull upon the link 38 and 60 will cause the slide 31 to be shifted toward

the stem c. Inasmuch as the lever 35 is locked in position it is obvious that as the slide 31 is drawn toward the stem it will wedge against the lever 35 and shift the lever 30 in a clockwise direction, thus turning 70 the throttle valve nearer to its fully closed position, or in other words reducing the amount of fuel which is discharged through the throttle valve to the engine and again, that as the speed decreases, the cylinder 75 16 will move rearward under the action of the springs 28 and this will push upon the link 37 and push the slide 31 toward the extremity of the portion 30 of the lever 29 and this will draw the lever 29 toward a position parallel to the lever 35 thus 80 opening the throttle valve and allowing a greater amount of fuel to pass to the engine.

It will be plain from Figure 1 that at any position of the slide 31, movement may be 85 communicated to the lever 29 and to the throttle, to close or open the throttle, by shifting the rod 36 either through the action of the hand lever L on the wheel or through the action of the accelerator pedal P. If the rod 90 36 be shifted by the action of the hand lever on the wheel, the lever 29 will be shifted accordingly. If, on the other hand, the rod 36 is shifted by the action of the accelerator pedal, the accelerator pedal when it returns 95 to its normal position will return the lever 35 to the position at which it was before the accelerator pedal was operated and thus the lever 35 and the lever 29 will both be returned to their normal positions. 100

It is to be particularly noted that the operation of the lever 35 by the accelerator pedal or by the hand controlled lever on the wheel does not in any way affect the position of the slide 31 and thus does not in any way 105 affect the governor. Thus the lever 35 may be set to cause the predetermined opening of the throttle valve and then the governor will operate to decrease the amount of fuel passing to the engine when the speed rises 110 above this point and thus maintains a more or less constant speed, and increase the amount of fuel passing to the engine when, for instance, the speed of the vehicle is decreased owing to its reaching the foot of a 115 hill.

It will be seen that the mechanism which I have illustrated and described acts to automatically regulate the feed of fuel to the engine while permitting the instant regulation of the throttle by means of the hand throttle control or the foot operated accelerator and that this mechanism causes the motor to maintain or tend to maintain a uniformity of speed over differences in the 120 grade of the roadway without necessitating any movement of the hand throttle control or the accelerator, the rate of speed, of course, being governed by the position of the throttle valve and varied by each move- 125 130

ment thereof. It will further be seen that the flow of fuel to the engine is subjected at all speeds to a dual control, namely, the control operated by the driver either through the accelerator pedal or the throttle controlling lever and the control operated by the speed of the motor and that these two instrumentalities do not interfere in any way with each other and that the governor control does not interfere in any degree with the direct connection between the control operated by the driver and the carburetor and does not change in any way the quickness of response of the motor to that control.

15 Furthermore, my invention provides means for automatically increasing the power of the motor driven vehicle regardless of its speed when a hill is approached, when the vehicle is going up the hill and causes a corresponding decrease in the power of the motor by cutting down the flow of fuel when the vehicle reaches the top of the hill.

20 This device eliminates much of the manipulation by the driver of the throttle controlling lever on the wheel and of the accelerator, thus making the driving of the vehicle much simpler, and the device has the further advantage that it economizes in gasoline.

25 It will be seen that in this mechanism the result of the automatic action of the governor is that the throttle is retarded to some extent by each increase in speed, held in that position until the motor starts to slow down, and is then retarded less, thus causing a greater feed of fuel. My mechanism is not one of those which is put into operation only after a certain speed of the engine has been reached but my mechanism operates under all speeds and under all speeds co- 30 operates with the hand or driver control.

35 Furthermore, it will be noted that with my mechanism the driver's control does not depend upon any change in the tension of the spring but that the driver's control is positively connected at all times with the throttle valve lever so as to secure an instantaneous change in position of the throttle valve at the will of the driver and while the vehicle is at full speed or at any other speed. The compression springs of my mechanism may be readily adjusted at any time. The governor mechanism in my case operates in a frame disposed at the side of the engine. This mechanism pulls toward the front of the machine and thus permits the application of the governor to the usual levers connected to the throttle. I have provided a very simple and practical means of transmitting action of the centrifugal governor to the throttle valve, however, retaining the control of the throttle valve at all times and under all speeds by means of the hand throttle lever or accelerator operating independently of the ac-

tion of the governor. It is pointed out that in my construction the adjustment of the manually controlled lever L or the accelerator pedal P has no effect on the governor because the link 37 is pivotally connected to the rod 38 and the movement of link 37 when rod 36 is shifted is transverse to the line of pull on rod 38. The throttle may thus be set by hand without shifting the governor arms or shifting the cylinder 16. On the other hand, the slightest movement of the governor arms affects the position of the throttle valve by changing the position of the freely oscillatable throttle lever 29 with reference to the previously set and, therefore, relatively fixed lever 35.

35 While I have illustrated certain details of construction and arrangement of parts which I have found to be particularly effective in actual practice, I do not wish to be limited thereto as many changes might be made therein without departing from the spirit of the invention as defined in the appended claims.

I claim:—

1. The combination with the fuel controlling means of an internal combustion engine and manually controllable means for setting said fuel controlling means to deliver a definite supply of fuel to thus attain a definite speed, of a shiftable member positively connected to the fuel controlling means, a second shiftable member, a speed responsive element operatively connecting both of said members for simultaneous movement in the same direction to open or close the fuel controlling means but shiftable under the action of the speed responsive element to shift the first named member relative to the second named manually set member.

2. The combination with the fuel controlling means of an internal combustion engine and manually controlled means for setting said fuel controlling means to deliver a definite supply of fuel to thus obtain a definite speed, of a shiftable member positively connected to the fuel controlling means to move therewith, a shiftable member operatively connected to the manually controlled means to be shifted thereby, a shiftable element mounted upon one of said members for shifting movement and slidably engaged with the other of said members and varying the position of said members relative to each other when the element is shifted, and a governor operatively connected to said element and driven by the engine, the governor acting to maintain the speed of the engine constant under variations of load said governor being entirely unaffected by any movement of the manually controlled means.

3. In a motor vehicle, the combination with the throttle valve of an internal combustion engine, manually operative adjust-

ing means therefor, and a speed controlled adjusting means therefor, of a member positively connected to the throttle valve for movement therewith, a second member connected to the manually adjustable means and adjustable to a set position, and a third shiftable member positively connecting the first and second members for unitary movement in the same direction and operatively connected to the speed responsive element to be shifted thereby and when shifted by the speed responsive element in one direction or the other shifting the first and second named members toward or from each other.

5 4. The combination with the throttle valve of an internal combustion engine and manually controlled means for setting said throttle valve to deliver a definite supply of fuel to thus obtain a definite speed, of a lever positively connected to the stem of the throttle valve to oscillate therewith, a second lever loosely mounted upon the stem of the throttle valve, a sliding member mounted 10 upon one of said levers and having sliding engagement with the other lever and shiftable along the first named lever to thereby vary the positions of said levers relative to each other, the second named lever being 15 operatively connected to the manually controlled means to be shifted thereby, and a centrifugal governor driven by the engine and operatively connected to said slide to shift the same along the lever on which the 20 slide is mounted.

5 5. The combination with the throttle valve of an internal combustion engine and manually controlled means for setting said throttle valve to deliver a definite supply of fuel 25 to the engine to thus obtain a definite speed thereof, of a lever mounted upon the stem of the throttle valve to oscillate therewith, a second lever loosely mounted upon the stem of the throttle valve and extending at 30 all times in angular relation to the first named lever, the second named lever at one end being operatively connected to the manually controlled means, a slide mounted upon the first named lever and having an arm 35 having sliding engagement with the second named lever whereby to cause relative movement of the two levers as the slide is shifted upon its lever, and an engine driven governor operatively connected to said slide.

5 6. The combination with the throttle valve of an internal combustion engine, manually operable adjusting means therefor and a speed controlled adjusting means therefor, of a member positively connected to the 40 throttle valve for oscillative movement therewith, a second member operatively connected to the manually adjustable means and adjustable to a set position around a center, and a third shiftable member positively connecting the first and second members for 45

unitary oscillative movement in the same direction and operatively connected to the speed responsive element to be shifted thereby in a direction radial to the center of the oscillative movement of the first and second members and when shifted by the speed responsive element changing the angular relation of the first and second named members. 70

7. In an internal combustion engine, a throttle valve, and means for controlling the 75 throttle valve including a centrifugal governor operated from the engine, a longitudinally movable cylinder, a shaft rotatable with the governor and longitudinally movable thereby and having swiveled engagement 80 with the cylinder, a support through which said cylinder operates, rods extending from said support toward the governor, arms mounted upon the cylinder and having apertures through which said rods pass, springs 85 surrounding said rods and bearing against said arms and resisting longitudinal movement of the cylinder in one direction under the action of the governor.

8. In an internal combustion engine, a 90 throttle valve, and means for controlling said throttle valve including a centrifugal governor, means for driving the governor from the engine, a longitudinally movable cylinder having a centrally apertured head 95 at one end, a shaft rotatable with the governor and longitudinally movable thereby, said shaft extending through the aperture in the head of the cylinder and having a head bearing against the inside face of the cylinder 100 head but rotatable within the cylinder, the outward movement of the governor under centrifugal action acting to shift the cylinder toward the governor, a bearing member within which the cylinder is supported for longitudinal movement and having outwardly projecting lugs, longitudinally extending rods mounted upon said lugs, arms carried by the cylinder and extending parallel thereto and having inturned perforated ends through which said rods pass, and springs carried by said rods and bearing against the inturned extremities 110 of the arms and resisting movement of the cylinder toward the governor. 115

9. In a motor vehicle having a fan shaft and a throttle valve, means for controlling the position of the throttle valve comprising a support mounted upon the vehicle at one side of and parallel to the engine, a shaft mounted at one end of the support and carrying a pulley, means operatively connecting the pulley to the fan shaft of the engine, a second shaft mounted at the other end of the shaft for rotatable and longitudinal movement, a centrifugal governor disposed between and operatively connected to both of said shafts, a cylinder mounted upon said support for longitudinal movement, the second named shaft having swiveled engage- 120 125 130

ment with the cylinder and acting to shift the cylinder toward the governor upon the outward movement of the governor under centrifugal force, springs resisting movement of the cylinder toward the governor, and operative connections from said cylinder to the throttle valve including a lever mounted upon the stem of the throttle valve for oscillation therewith, a slide mounted upon the lever and having a laterally projecting arm, a connection from the cylinder to said slide, a second lever mounted loosely upon the stem of the throttle valve and disposed in angular relation to the first named lever, the laterally projecting arm of the slide having sliding engagement with the second named lever, and manually operable means for adjusting the second named lever.

15 In testimony whereof I hereunto affix my signature.

EDWARD A. ROBB.
